CLAIM

I claim the ornamental design for a vibration dampener for a sports racquet, as shown and described.

DESCRIPTION

FIG. 1 is a side view of the vibration dampener for sports racquet;

FIG. 2 is a top plan view thereof;

FIG. 3 is a perspective view thereof;

FIG. 4 is a bottom plan view thereof;

FIG. 5 is a side view thereof, opposite of that disclosed in FIG. 1;

FIG. 6 is an end view of FIG. 1; and,

FIG. 7 is an end view of FIG. 1, opposite of that disclosed in FIG. 6.
